UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

AUTOMATIC CLIP-OPERATING MEANS FOR STEREOTYPE MOLDS

Application filed January 19, 1927, Serial No. 162,117. Renewed September 5, 1929.

This invention relates to automatic mechanism by which the matrix clips are locked and released at the proper time, controlled by the operation of the machine; specifically by the movement of the back. The principal objects of the invention are to provide such an automatic means to save the time required for accomplishing these operations by hand, as has heretofore been done, and especially to avoid the danger that the operator will fail at some time to unlock the clips before he starts the casting operation, thus causing breakage of the clips or other long or expensive delays.

Other objects and advantages of the invention will appear hereinafter.

Reference is to be had to the accompanying drawings in which

Fig. 1 is a plan of a casting box for a stereotype printing plate with the riser omitted to show the plate as cast and the mold closed;

Fig. 2 is a side view of the same with the parts in the same position;

Fig. 3 is a front view as indicated by the arrow 3 in Fig. 1 showing the parts in the same position;

Fig. 4 is a plan similar to Fig. 1 showing the position of the parts when the back has been drawn rearwardly part way;

Fig. 5 is a similar plan showing the mold almost completely open; and

Fig. 6 is a similar plan showing the final open position of the mold.

The clamping of the matrix by the clips in a stereotype plate casting machine involves several distinct motions. In closing the mold from a full open position, the clips are first placed in a half cocked position so that while the back is in its extreme open position they are open enough so that the matrix can be inserted. Then the clips are usually moved into the full cocked position by hand to grip the matrix at its edges. This operation is ordinarily performed by a hand-operated toggle lever. Then the clips are released again so that the matrix is left in proper position to be brought against the back and the clips can be operated by the core when the mold closes to hold the matrix positively.

This latter is the final operation in closing the mold. These operations have been performed by hand heretofore, usually by two hand levers, and they have to be performed while the mold is being closed and when it is being opened in the reverse order. This takes the attention of the operator for a short period of time it is true, but still, enough so that the time saved by this invention is of value. Further, the danger of the operator not getting the clips unlocked before the casting box is moved up to the core is avoided and his attention can be devoted to other things.

In the drawings, I have shown the order of steps in opening the mold. In Figs. 1, 2 and 3 the mold is shown in casting position and all the parts are in the positions they occupy at that time.

I have shown the cylindrical core 10 and segmental back 11 of the usual construction with a plate P cast therein against the matrix M. As usual, a projection or cam 12 on the cylinder is at this time in engagement with an arm 13 on a vertical shaft 14 to hold this arm in the position shown and swing the shaft to that position. Of course, these parts are repeated on the other side. This compresses a spring 15 on the shaft 14 which is connected in a well known way to swing that shaft back when the mold and core separate. On that shaft is the matrix bar 24 and also an arm 16 which is provided with two notches 17 and 18 and a cam surface 19.

In Fig. 1 the projection or cam 12 on the cylinder 10 holds the arm 16 out practically in radial direction where it is not in contact with the other operating elements.

Pivoted on the back is the toggle lever 20 which by an adjustable link 21 is connected to the matrix clip 22. At this time the matrix clip 22 is pushed back to clamp the edge of the matrix against the casting bar 24 which is also on the shaft 14. The clips 22 are slidingly carried by the shafts 14 through 95 the bars 24 on which they are mounted. It will be noted that in this case, instead of having a manually operated handle, the lever 20 is provided with a roller 25 which is now free but has been set in a position in which

it is shown in these three figures by a cam 26 on the stationary frame 27 of the machine. I have shown in Fig. 2 other dotted positions of the roller 25 to show that when the roll moves back this cam will later control this toggle lever 20 and perform certain operations as will appear hereinafter.

For the operation of the arm 16 and therefore the shaft 14 and matrix bar 24 I have described the spring 15. This is not free to open the bar 24 at the sides after the mold is open, because the back is provided with two locking levers 30 pivoted on vertical axes at each side. This lever has a roll or projection 31 adapted to engage the cam surfaces 17, 18 and 19 of the arm 16 and control the operation thereof. The lever itself is provided with another roll or projection 32 which is controlled by a fixed cam 33 on the frame 27 projecting over the top of the back. It will be seen that this cam is provided with three straight sections 34, 35 and 36 and two angular sections 37 and 38.

With this description of the parts, I will describe the operation of opening the mold from the position shown in the first three figures. The next position illustrated is that shown in Fig. 4 in which the back is drawn away from the core or cylinder part way, far enough so that the springs 15 have rotated the shafts 14 as far as the levers 30 will allow them to go. The roll 31 has now been engaged by the cam surface 19 and the rocking of the shaft 14 is thereby limited. This brings the bar 24 out and swings the edge of the matrix out from the back and strips it therefrom but the matrix clips 22 still hold it at its edges against the bars 24. There has been no change in the position of the lever 30 except that it has moved back along the straight section 34 with the back.

Now as the back moves further, to the position shown in Fig. 5 in which it is nearly back in wide open position, the roll 32 runs along the incline 37 and swings the lever 30 until the roll 31 enters the larger notch 17 and comes up against the stop at the end thereof. This forces the shaft 14 and bar 24 back into the same position as in casting and returns the matrix to its seat in the back. Also at this time the roll 25 has entered the cam 26 and is being held in its normal position with the matrix clips still clamping the matrix.

This would be all that would be necessary if the same matrix were to be used over and over but sometimes the matrix has to be removed and replaced. Therefore, I provide means whereby the matrix is released if the back is drawn one step further back. That is shown in Fig. 6. Here the roll 32 has gone up the incline 38 into the straight section 36 which brings the roll 31 into the notch 18. This turns the shaft 14 back to hold the matrix bar 24 back in its extreme position. At the same time the operation of the toggle

20 by the roll 25 being shifted by the incline 26, causes the matrix clips 22 on both sides to be released as shown in Fig. 6. The matrix can be removed and replaced.

Whether that is done or not, the first operation necessary in closing the mold from this position releases the roll 31 from the notch 18 and leaves it in the notch 17, on account of the reverse motion of the back, and clamps the matrix. As the mold further closes, the parts go through the position shown in Fig. 4. During this closing operation, it will be noted the clips are unlocked by the toggle lever 20, after the matrix has been locked, so that the cams 12 on the core can perform the locking operation themselves. When it is desired to change matrices, the operator will merely move the casting box to its extreme rear position, Fig. 6, which will cause the locking lever 30 to first move the clips to the full-cocked position shown in Fig. 5. Movement beyond this point causes the toggle lever 20 to open the matrix bars, releasing the pinch on the matrix. Further movement on the part of the casting box will cause it to occupy the extreme position shown in Fig. 6 where the clips are thrown into a half-cocked position, permitting the removal of the matrix. When it is desired to insert a new matrix the several parts perform the same operations in the reverse manner. If the clips were not unlocked before the casting operation was started, a serious accident would happen, such as the breaking of the matrix clips. This would unnecessarily delay the casting operation.

Although I have illustrated and described only a single form of my invention I am aware of the fact that modifications can be made therein by any person skilled in the art without departing from the scope of the invention as expressed in the claims.

Therefore, I do not wish to be limited to all the details of construction herein shown and described but what I do claim is:—

1. In a stereotype plate casting mold, the combination with the core, back and matrix clips carried by the back, of means for automatically moving the clips into a half-cocked position when the mold is wide open, means for automatically moving the clips to clamp the matrix at its edges as the mold closes, means for releasing the clips, and means whereby the closing of the mold will operate the clips at the proper time to grip the matrix.

2. In a stereotype plate casting mold, the combination of a pair of shafts along the edges of the mold, means for normally turning the shafts in one direction, matrix clips carried by the shafts, a lever for operating the clips to grip the matrix when the shafts are turned in opposition to said shaft turning means, an arm on each shaft having the cam surfaces for controlling the motion of the

shaft, and a stationary cam for controlling the motions of said lever and thereby the motions of the matrix clips automatically.

3. In a stereotype printing plate casting machine, the combination with a two part mold, of two shafts at the sides thereof, matrix bars on said shafts, means for normally swinging the shafts to a position in which the matrix bars are open, and stationary cams in position for operating the matrix bars when the mold is wide open to release them, then clamp them in position while the mold closes, and release them so that the complete closing of the mold will clamp them again.

4. The combination with a stereotype plate mold and its matrix clamping means, of an arm connected with said means for controlling the motion and having a cam surface and two notches therein, of a lever pivoted on the mold and having means for engaging said cam surface and notches, in accordance with the position of the lever, to control the matrix bars, and stationary means for moving said lever to different positions governed by the opening and closing of the mold.

5. In a stereotype plate casting mold, the combination with a shaft having a matrix bar for closing the edge of the mold, said shaft having an arm projecting therefrom, of a lever for engaging said arm and controlling the position of the bar, and a stationary cam having a slot into which a part of the lever projects to control the swinging of the lever on its axis, said cam having a groove provided with three parallel parts, one for keeping the lever in the position in which it is located during casting, one for holding it in a position to close the bar and the third in position to release the bar, said cam grooves being connected by sections of the groove at an angle thereto.

6. In a stereotype plate casting mold the combination with matrix bars mounted to swing on parallel axes at the sides of the mold, clips movably mounted thereon, toggle levers on the bars for operating the clips to pinch the edges of the matrix, a movable back on which said parts are mounted, and stationary cams for operating the matrix clips as the back moves.

7. In a stereotype plate casting mold, the combination of a pair of shafts along the edges of the mold, springs for normally turning the shafts in one direction, matrix clips carried by the shafts, means for operating the clips to grip the matrix when the shafts are turned in opposition to the springs, an arm on each shaft having a cam surface for controlling the motion of the shaft, said clip operating means comprising a lever pivoted on the mold and movable with it and a stationary cam for controlling the motions of said lever and thereby the motions of the matrix clips automatically.

8. In a stereotype plate casting mold, the combination with the core, back and matrix clips carried by the back, of means for automatically moving the clips into a position to release the matrix by the movement of one of the parts of the mold away from the other to wide open position.

9. In a stereotype plate casting mold, the combination with the core, back and matrix clips carried by the back, of a shaft along the edge of the back, a matrix clip carried by the shaft, and means in stationary position for turning the shaft as the back moves away from the core to open position to move the clip into a position to release the matrix.

10. In a stereotype plate casting mold, the combination with the core, back and matrix clips carried by the back, of means for automatically moving the clips to clamp the matrix at its edges as the mold closes at the proper time to grip the matrix, and means for releasing the clips automatically by the action of the mold in moving to wide open position.

11. In a stereotype plate casting mold, the combination with the back and core, of matrix bars at the sides of the back, a lever pivoted on the back and having means for moving said matrix bars, and stationary means located in position for operating said lever to different positions upon the opening and closing of the back.

12. In a stereotype plate casting mold, the combination with the back and core, of matrix bars at the sides of the back, a lever pivoted on the back and having means for moving said matrix bars, stationary means located in position for operating said lever to different positions upon the opening and closing of the back, and means on the core for positively locking the matrix bars in casting position when the mold is closed.

In testimony whereof I have hereunto affixed my signature.

HENRY A. WISE WOOD.
